UNITED STATES PATENT OFFICE.

CHARLES J. GUSTAVESON, OF SALT LAKE CITY, UTAH TERRITORY.

DEVICE FOR DESTROYING INSECTS.

SPECIFICATION forming part of Letters Patent No. 294,616, dated March 4, 1884.

Application filed May 28, 1883. (No model.)

To all whom it may concern:

Be it known that I, CHARLES J. GUSTAVESON, of Salt Lake City, in the county of Salt Lake, Utah Territory, have invented a new and useful Improvement in Devices for Destroying Insects, &c.; and I do hereby declare that the following is a full, clear, and exact description of the same, reference being had to the accompanying drawings, forming part 10 of this specification, in which—

Figure 1 is a side view partly in section, and Fig. 2 is a detail showing the attachment of a sprinkler to the receptacle B.

My invention relates to a novel construction of device for destroying insects by fumigation, and which is also applicable for use as a disinfecting apparatus, or for administering medicine or vapor baths, and which may also be used for sprinkling clothes, flowers, &c.

20 It relates to that class of apparatus in which a spirit-lamp is located beneath a vessel for generating steam, which vessel is provided with a flexible pipe for directing the jet to any desired point.

25 My invention consists in the peculiar construction of the apparatus, as will be herein-after fully described.

In the drawings, A represents the spirit-lamp, and B is the vessel which contains 30 the water or other liquid to be evaporated. For sustaining the vessel B above the lamp and at any distance above its flame, the said lamp is provided with a single upwardly-projecting standard, C, which is in the nature of 35 a spring, which, when free to assume its normal position, is curved. Upon the side of the vessel B are two loops or keepers, a a, one above the other, and of a width to receive the standard C. When the standard C is entered through 40 these loops, it becomes straightened to a vertical line, as in Fig. 1, in which position it supports the vessel B above the lamp in a manner that permits it to be slid up and down on the standard and maintained at any adjustment by the simple frictional contact of the 45 curved spring C in being straightened to the side of the vessel. This constitutes a very simple and efficient means for both sustaining and adjusting the vessel B by one and the same device.

50 In the adjustment of the vessel over the spirit-lamp it is my intention to make the said vessel, when not in use, to slide down and

rest with its bottom directly upon the wick-tube of the spirit-lamp, as shown in dotted lines, which is thus sealed against the evaporation and loss of alcohol.

55 In constructing the vessel B its bottom is made concave on the outside, and curves upwardly and inwardly at the center. The object of this is to give a larger and better heating-surface for the vessel, and this form also strengthens and braces this end of the vessel and prevents it also from becoming pierced with holes and rendered leaky by being set upon any sharp object.

60 At the upper end of the vessel B is a screw-neck, D, which, when the device is being used, is covered steam-tight by a cap, E.

For directing the steam or vaporized liquids to any desired point, a nipple or short tube, 7c b, is placed at the upper end of the vessel B, and over it is fastened a gum tube, F, having at its end a tapered nozzle, c, for directing the jet into small crevices and inaccessible places. To hold this tube in any position in which it 75 may be placed, I arrange inside of it a supporting-wire, d, which is provided with a sleeve, e, at its end that fits in the nipple b of the vessel and swivels or turns freely therein, but fits with sufficient frictional contact to 80 maintain the supporting-wire in any position in which it may be placed. This avoids the necessity of holding onto the tube with the fingers, which tube becomes highly heated by the steam.

85 In making use of my invention I may employ it in the form shown as an insect-destroyer, in which case such volatilizable materials are placed in vessel B as generate fumes poisonous to insects, or it may be employed for disinfecting or fumigating a sick-room, in which case a small quantity of carbolic acid, perfume, or medicinal substance may be evaporated with the water, or water alone may be evaporated, to correct dryness of the atmosphere. 90 Furthermore, it may be used as a portable vapor bath by placing a blanket around the patient and putting the apparatus to work beneath the chair upon which the patient sits; or as a further use I may employ the vessel 100 B as a sprinkling device by putting a perforated rose, G, in the place of the screw-cap at the top and stopping up the nipple b.

H is a curved handle for transporting the

device. This handle has its ends bent and adapted to fit under the keepers *a a*, and press against the spring-standard C, so that it not only acts as a handle, but also as an aid in holding the vessel B on the standard by pressing the latter into firmer frictional contact with the former.

Having thus described my invention, what I claim as new is—

- 10 1. The combination of the lamp A, having the single bent spring-standard C, with the vessel B, having loops or keepers *a a* for sustaining and adjusting the vessel above the lamp, as described.
- 15 2. The combination, with the lamp A, having standard C, of the vessel B, made adjustable thereon, and adapted to slide down and

rest upon the wick-tube to form a cover for the same, as described.

3. The combination, with vessel B, having 20 nipple *b*, of the flexible tube F and internal supporting-wire, *d*, with friction-sleeve *e*, substantially as shown and described.

4. The combination, with the standard C and vessel B, having keepers *a a*, of the curved 25 handle H, having its ends secured along with the standard in said keepers, as shown and described.

CHARLES J. GUSTAVESON.
